FIG. 3.

FIG. 4.

Attorney

UNITED STATES PATENT OFFICE.

JOHN L. FLATOW, OF WASHINGTON, DISTRICT OF COLUMBIA.

GAME.

1,374,844.

Specification of Letters Patent. Patented Apr. 12, 1921.

Application filed October 22, 1920. Serial No. 418,635.

To all whom it may concern:

Be it known that I, JOHN L. FLATOW, a citizen of the United States, and a resident of Washington, in the District of Columbia, 5 have invented certain new and useful Improvements in Games, of which the following is a specification.

This invention relates to apparatus for playing games of chance and has special 10 reference to that class of games in which balls or rolling objects are caused to travel over a field to a pocket or goal, the field being wholly or partly covered with obstacles to interrupt and turn aside the traveling objects.

One object of the present invention is to provide a novel gate for controlling the admission of an object to the goal.

Other objects will appear in the course 20 of the following description.

In the accompanying drawings, wherein corresponding reference numerals are used to indicate corresponding parts in each of the several views—

25 Figure 1 is a perspective view of a game apparatus embodying my present invention.

Fig. 2 is a longitudinal section.

Fig. 3 is a plan view, and

30 Fig. 4 is an enlarged detail section showing the operation of the gate.

In carrying out my invention I employ a table 1, which is supported in an inclined position by legs 2, of any desired design. Upon the table, at the sides thereof, I secure rails 3 which terminate short of the lower end of the table and from the lower ends of the rails 3, short rails 4 converge somewhat downward and terminate near and at opposite sides of the medial longitudinal line of the table. From the inner lower ends of the rails 4, parallel rails 5 extend to the lower end of the table, said rails 40 5 constituting the side walls of the goal or pocket and a cross plate 6 closing the lower 45 end of the pocket.

Throughout the area of the table between the rails 4 and the upper end of the table, are obstacles consisting of pins 7, secured in the table and projecting from the upper 50 surface of the same at a right angle thereto. These pins may be provided in any desired number and are arranged equidistantly but in staggered relation as shown most clearly in Fig. 3.

55 Inverted cups or shells 8, of brass, leather or any desired material, are loosely fitted on

the upper ends of the pins 7, to receive the impact of the balls or other objects and prevent chipping or marring of the surface thereof. As the cups or shells 8 are loose 60 on the pins, they not only shield or guard the pins and balls from injury but will rotate freely on the pins when engaged by a ball and so present an unstable support which will prevent a ball lodging against 65 a pin and failing to roll to the lower end of the table. The balls 9 are discharged onto the table by and from a holder 10, which is hinged to the upper end of the table and may be of any preferred form, the requisite being that it serve as a cup when lowered as shown, to hold the balls, and when swung upward will permit the balls to gravitate or roll onto the table.

In the larger sizes of the apparatus, the 75 holder may be controlled by a cable or chain 11, secured at one end to the holder and passing upward therefrom to a guide pulley 12, supported in any convenient manner, and thence to a second guide pulley 13, from 80 which its free end depends. A handle or grip 14 of any desired form may be secured on the extremity of the cable.

In the small toy sizes the cable may be omitted and the holder 10 actuated by the 85 hand direct.

The rails 5 are spaced apart a distance slightly greater than the diameter of a ball 9, so that while any one ball may enter the goal easily only one ball may pass at one 90 time. The admission of one ball to the goal and the barring of subsequent balls is accomplished automatically by a gate 15 which consists of a plate disposed longitudinally of the goal and provided between its ends 95 with a transverse baffle 16. The plate is also provided at its edges with lugs or ears 17 receiving pivots 18 fitted through posts 19 or other supports. In this floor of the goal or pocket and near the entrance thereto 100 there is an exit opening 20, from which a return way 21 leads to a trough or other receptacle 22 supported on the legs 2, below the holder, 10. The exit opening is normally covered by a slide 23 fitted in grooves 105 in the inner faces of the rails 5, and projecting beyond the stop 6, the end of the slide resting upon a bracket 24 secured on the table and a pin 25 being inserted through the end of the slide and the said 110 bracket to hold the slide normally against movement.

In the initial position the balls are disposed in the holder in a row extending across the end of the table and the gate has its front end bearing upon the floor 5 of the pocket and its baffle projecting toward the entrance as shown in Fig. 2. The holder 10 being swung upward the balls will be delivered upon the table and will roll down the inclined surface of the same to the rails 10 4 and being deflected by them toward the goal or pocket. One of the balls will enter the goal and ride against the baffle 16, the impact causing the baffle to swing rearwardly and turn the gate to the position 15 shown in full lines in Fig. 4, in which its front end rests upon the slide 23. The ball striking the baffle will thus be permitted to pass to the lower front end of the goal and will be declared the winner while the 20 remaining balls will be held by the rear end of the gate and it will be noted that the rear end of the gate is rolled or curved as at 26 to more readily pass between the advancing balls. The balls are numbered and 25 the players will be furnished tokens bearing corresponding numbers, the player holding the number corresponding to the number on the ball which passes the gate being entitled to whatever prize may be offered. 30 After the winner has been determined the pin 25 is released and the slide drawn forward, whereupon the gate will swing to the position shown in dotted lines in Fig. 4 and the balls will enter the return way 21 35 and pass through the same to the receptacle 22 whence they may be transferred to the holder 10 by an attendant. The winning ball may be placed in the return way by the operator in charge of the game who will 40 also manually set the gate in its initial position and reset the slide 23.

The balls obviously will be deflected and diverted by the obstacles 7 and 8 and the 45 progress of the several balls over the table may be observed by the players whose interest will be aroused and intensified as one ball and then another seems to be in the lead to the goal.

Having thus fully described my invention, what I claim as new and desire to secure by Letters Patent of the United States, is—

1. A game apparatus comprising an inclined table, a goal at the lower end of the

table, a plurality of rolling objects to travel over the table to the goal, and a gate mounted in the goal for swinging movement in a vertical plane constructed and arranged to be actuated by one of the rolling objects whereby to admit the same to the goal and exclude the remaining objects. 60

2. A game apparatus comprising an inclined table, a goal at the lower end of the table, a plurality of rolling objects to travel over the table to the goal, and a gate mounted in the goal for swinging movement in a vertical plane and having a baffle on its under side to be actuated by one of the rolling objects whereby to admit the same to the goal and exclude the remaining objects. 65

3. A game apparatus comprising an inclined table, a goal at the lower end of the table, a plurality of rolling objects to travel over the table to the goal, a gate mounted to rock in a vertical plane longitudinally of the goal and bear at either end upon the bottom of the goal, and a transverse baffle on the under side of the gate adapted to receive the impact of a rolling object entering the goal whereby to lift the front end of the gate and cause the rear end thereof to bear upon the bottom permitting the impacting object to pass and arresting the travel of the succeeding objects. 70

4. A game apparatus, comprising an inclined table, a goal at the lower end of the table, a plurality of rolling objects to travel over the table to the goal, an exit in the floor of the goal, a slide upon said floor normally covering said exit, and a rocking gate arranged to be actuated by a rolling object entering the goal to cause its rear end to bear upon the slide over the exit and arrest travel of subsequent objects, the withdrawal of the slide permitting the end of the gate to swing across the exit and admit the rolling objects thereto. 75

5. A game apparatus, comprising an inclined table, a plurality of rolling objects adapted to travel by gravity over the table, a goal at the lower end of the table, and means actuated by one of the rolling objects to control the admission of said object to the goal and arrest or exclude the remaining objects. 80

JOHN L. FLATOW.
